UNITED STATES PATENT OFFICE.

EMMA J. RAWLINGS, OF ST. LOUIS, MISSOURI.

PILLOW-SHAM SUPPORT.

SPECIFICATION forming part of Letters Patent No. 269,880, dated January 2, 1883.

Application filed June 19, 1882. (No model.)

To all whom it may concern:

Be it known that I, EMMA J. RAWLINGS, of St. Louis, in the county of St. Louis and State of Missouri, have invented an Improved Pillow-Sham Support; and I do hereby declare that the following is a full and exact description thereof, reference being had to the accompanying drawings, making part of this specification—

- 10 Figure 1 representing the pillow-sham support as applied to a bedstead; Fig. 2, a view of the supporting-rod, showing the mode of attaching the pillow-shams thereto and holding them stretched thereon; Fig. 3, a view of the 15 supporting-rod, showing its two parts folded together; Fig. 4, a front view of the adjustable main hook with its attaching-plate; Fig. 5, a side view of the same; Fig. 6, a view in perspective of a removable auxiliary hook; 20 Fig. 7, a view showing the two hooks combined.

Like letters designate corresponding parts in all of the figures.

My invention consists in a simple cheaply-25 constructed pillow-sham support, neat in appearance, readily attached to any bedstead, quickly removed, and practical in its use.

I have shown in Fig. 1 the general arrangement of this invention and the mode of applying it to a bedstead. This will be readily understood from a description of the several parts composing the invention, which I now proceed to set forth.

First, I employ a rod, A, of sufficient length 35 to extend across the width of a bedstead. This supporting-rod is shown in Fig. 2, with the pillow-shams B B attached to it by means of loops a a, strung upon the same, and held stretched thereon by means of rubber bands b b, tightly fitting upon the rod inside of the outer loops of each sham, as represented. This rod may be made of wood or metal, preferably of wood, and of varying lengths, that it may be adapted to different widths of bedsteads.

40 For convenience in laying aside or packing away when not in use, especially for double bedsteads, the supporting-rod is preferably made in two parts hinged together at their adjacent ends, so that they may be folded together, as shown in Fig. 3. The two parts are held rigidly extended by a metallic sleeve, c, fitting closely thereon, as indicated in Fig. 2, and sliding to one side of the joint, as seen in Fig. 3, when the rod is doubled up.

For supporting the rod, with the shams attached thereto, against the head of the bedstead, I employ simple hooks C C, Figs. 4 and 5, using two for a bedstead. Each hook is provided with an attaching-plate, D, which has screw-holes d d for securing the same to the bedstead by ordinary wood-screws. These may be secured to the bed-posts, as shown in Fig. 1, or attached to the head-board in any other convenient way; and in order to adapt the hook to different constructions of bedsteads, 65 so as to always bring them just in front of the head-board, they have shanks f f of considerable length, as shown in Fig. 5, which fit in tubular bearings g g in the attaching-plates D D, so that the hooks may slide forward or 70 backward therein, as required. Ordinarily this is sufficient; but in some cases it may be necessary or desirable to have the hooks extend farther forward than the length of shank ordinarily given to it will permit. In such 75 cases I make use of auxiliary movable hooks E E, Fig. 6, each provided with an eye, h, for suspending it from the main hook, as seen in Fig. 7. In this case the supporting-rod rests in the auxiliary hooks. 8c

What I claim as my invention, and desire to secure by Letters Patent, is—

1. The supporting-rod A, provided with the rubber rings b b, in combination with the pillow-shams B B, substantially as and for the 85 purpose herein specified.

2. The main supporting-hooks C C, provided with the attaching-plates D D, substantially as and for the purpose herein specified.

3. The hooks C C, arranged to slide in bearings g g in the attaching-plates, substantially as and for the purpose herein specified. 90

4. The auxiliary hooks E E, provided with eyes h h, in combination with the main hooks C C, substantially as and for the purpose herein specified. 95

5. A pillow-sham support composed of a rod, A, with rubber rings b b thereon, and hooks C C, with the attaching-plates D D, with or without the auxiliary hooks E E, substantially 100 as and for the purpose herein specified.

EMMA J. RAWLINGS.
